UNITED STATES PATENT OFFICE.

JOHN SCHURY, OF DETROIT, MICHIGAN.

MULTIPLE FUSE.

Application filed April 15, 1922. Serial No. 553,156.

To all whom it may concern:

Be it known that I, JOHN SCHURY, a citizen of Austria, residing at Detroit, in the county of Wayne and State of Michigan, have invented certain new and useful Improvements in Multiple Fuses, of which the following is a specification, reference being had therein to the accompanying drawings.

This invention relates to fuses and has special reference to multiple fuses wherein rotary plugs are provided with a plurality of fuses that may be successively shifted to active positions, thus permitting of a good fuse being substituted for a blown-out fuse, and such fuses obviate the necessity of using individual fuses when electric circuits are to be completed.

My invention aims to provide a multiple fuse which is sealed and cannot be conveniently tampered with after the parts of the fuse are assembled, thus providing a fuse which meets with the requirements of the Underwriters' Association pertaining to such matters.

25 My invention further aims to furnish a fuse of the above class with a spring pressed contact member of a configuration which will not interfere with rotations of a multiple fuse plug and which will at all times insure a positive contact with one of the fuses of the plug.

30 My invention further aims to accomplish the above results by a durable and inexpensive construction that will be hereinafter described and then claimed and reference will now be had to the drawing, wherein—

Figure 1 is a view of one side of a multiple fuse in accordance with my invention;

Fig. 2 is a view of the opposite side of the fuse;

Fig. 3 is a longitudinal sectional view of the fuse;

Fig. 4 is a horizontal sectional view taken on the line 4—4 of Fig. 3;

45 Fig. 5 is a side elevation of the rotatable plug provided with a multiple fuse;

Fig. 6 is a view of the inner end of the same;

Fig. 7 is a perspective view of the multiple fuse per se;

Fig. 8 is a plan of a blank multiple fuse,

Fig. 9 is a view of the outer end of the complete fuse as shown in Figs. 1 to 3 inclusive, and

55 Fig. 10 is a horizontal sectional view taken on the line 9—9 of Fig. 3.

In the drawing, the reference numeral 1 denotes a cylindrical body made of a suitable insulation material, and said body is exteriorly screwthreaded, as at 2, to receive 60 a screw cap 3 having a central opening 4. The cap 3, about the opening 4, is provided with indicia 5 relative to the number of fuses within the fuse body.

The body 1 has an exteriorly screwthreaded reduced end 6 on which is mounted a sleeve 7, said sleeve being also screwthreaded so that the reduced end of the fuse body may be screwed into a socket in the usual manner. The reduced end 6 of the fuse 70 body terminates in a nose 8, and said fuse body has a large cylindrical chamber 9 extending from the inner end of the body 1 into the reduced end 6 thereof and said chamber, within the reduced end 6, has 75 longitudinal equally spaced ribs 10 on a semi-cylindrical portion of its wall cooperating with the remaining portion of the wall in forming end abutments 11.

In the chamber 9, at the nose end of the 80 body 1 is a central frustro conical shaped boss 12 and axially of said boss is a terminal 13 having an inner contact member 14 and an outer contact member 15. The outer contact member 15 is adapted to establish electrical connection when the fuse body is 85 screwed into a socket.

The chamber 9, at the inner end of the body 1 has a wall recess 37 communicating with an opening 16 in said body at the reduced end 6 thereof, and the shell 7 extends to the mouth of said opening, so that said shell may be soldered or otherwise connected, as at 17 to a spring pressed contact member 18 set in the wall recess 37. With one 95 end of the contact member 18 soldered to the shell 6 the opposite end of said contact member may be sprung and it is this end of the contact member that is engaged by a coiled expansion spring 19 set in the recess 37. 100 The expansive force of the spring 19 forces the end of the contact member outwardly from the recess 37 and said contact member has a bent or cam edge 20 by which the contact member may be forcibly caused to 105 recede into the recess 37, when switching from one fuse to another as will hereinafter appear. The end of the contact member 18 is bent outwardly to form a lip 21 so as not to interfere with the insertion of a plug 110 in the body 1, and the manner in which the contact member is mounted prevents said

contact member or the spring 19 from becoming accidentally displaced.

The reference numeral 22 denotes an inverted frustro conical shaped plug provided with a head 23, a peripheral flange 24 and a tang or finger piece 25. The plug is made of a suitable insulation material and is placed in the chamber 9 with the flange 24 engaging the cap 3 and the head 23 extending through the opening 4 of the cap, so that the tang or finger piece 25 will be exposed for rotating the plug. On the head 23 or the tang 25 may be placed indicia relative to direction of rotation of said plug, also 15 the number of amperes for which fuses are intended.

The plug 22 has an inner reduced end 26 provided with a concave recess 27, and the outer walls of said plug are provided with 20 longitudinal grooves 28 communicating with notches 29 in the lower face of the flange 24. The recess 27 has its walls notched, as at 30 with the notches opening into the grooves 28, and the plug 22 has an annular shoulder 25 31 which will engage the abutments 11 and limit the inward movement of the plug should such limitation be necessary.

The reference numeral 32 denotes a multiple fuse blank or spider having a plurality of radially disposed fuses 33 provided with neck portions 34 connecting the fuses to the spider or blank 32, and these multiple fuses are adapted to be cut and stamped from sheet metal of such gauges as 35 will afford fuses of various thicknesses. The metal used for the fuses is of a fusible nature of predetermined conductivity and the thickness or strength of each fuse will determine the amperes that may be safely 40 carried thereby, any overload causing the fuse to burn or blow out.

The fuse spider or blank 32 is shaped to fit in the recess 27 with the neck portions 34 engaging in the notches 30 and the fuses 33 45 extending along grooves 28 into the notches 29. In practice, the fuse blanks are bent and mounted on or in the plugs by a special machine designed for such purpose, and with the fuse blank or spider 32 providing 50 an inner lining for the recess 27, said fuse blank or spider will contact with the contact member 14 of the terminal 13. The boss 12 has a configuration cooperating with the contact member 14 in permitting the 55 plug to be fitted down over the contact member 14 and rotated thereon. The plug is adapted to be turned in a clockwise direction so that the ribs formed by the grooves 28 will impinge against the cam edge 20 of 60 the contact member 18 and cause said member to recede until it may rebound into one of the grooves 28 and engage the fuse 33 therein. By reference to Fig. 4, it will be noted that the grooves 28 are of sufficient 65 width to receive the contact member 18 and

when the plug 22 is rotated in a clockwise direction there is a snap action as the contact member 18 enters the groove. This snap action will permit of the operator of the fuse plug determining when the plug has 70 been sufficiently rotated to install a new fuse in the place of a burned out fuse, which place is always in proximity to the contact member 18, as the other fuses remain idle as long as there is an operative 75 fuse at the contact member 18. However, the other fuses 33 are always in position to be shifted into use, and after all of the fuses 33 have been used, it is possible to install a new fuse blank or spider and thus renew 80 the multiple fuse, without discarding the body or plug thereof. In some instances such renewal, particularly by the user, is prohibitive so in order to prevent such practice I may seal or fix the cap 3 to prevent its 85 removal and access to the plug 22. This is accomplished by providing the body 1 with one or more notches 35 and depressing or indenting the cap 3, as at 36 until said cap enters the notch and cannot be rotated. The 90 indenting of the cap may be easily accomplished by a special die and after the cap is so locked on the body it cannot be conveniently removed, and consequently the user of the fuse cannot reload the fuse body with 95 fuses that may be of greater strength than actually intended for a safe electric circuit.

I attach considerable importance to the construction of the contact member, also the ribs on the inner walls of the insulator body, 100 as these ribs reduce the frictional contact between the plug and the body so that with the plug bearing on the terminal of the body there is no danger of the walls of the plug binding against the walls of the body and 105 interfering with rotation of the plug in the body. Furthermore, the ends of the ribs being end abutments and should there be any inequalities of manufacture, the forward movement of the plug will be limited by 110 such end abutments.

The indicia associated with the cap 3 and the plug 22 will permit of the user of the plug ascertaining what fuses have been burned out and the remaining usefulness of 115 the multiple fuse, and while in the drawing there is illustrated a preferred embodiment of my invention, it is to be understood that the structural elements are susceptible to such variations and modifications as fall 120 within the scope of the appended claims.

What I claim is:—

1. In a multiple fuse wherein a rotary plug is mounted in a body adapted to be mounted in a socket, and fuses carried by 125 said plug are adapted to be brought successively into electrical connection with the socket;—means for establishing such connection, said means comprising a contact member in said body adapted to be engaged 130

by the fuses of said plug, said contact member having an end lip to facilitate mounting said plug in said body and a cam edge to facilitate rotation of said plug in said body, and an expansion spring between said body and contact member to insure a positive engagement between said contact member and said plug fuses.

2. In a multiple fuse wherein a rotary 10 fuse carrying plug is mounted in a body and adapted to be rotated therein, to establish an electrical connection;—means supporting said plug for easy rotation in said body,

said means comprising a terminal in said body, and ribs on the inner walls of said body reducing the frictional contact between said body and said plug.

3. A multiple fuse as in claim 2, wherein the ribs on said body afford end abutments to limit inward movement of said plug. 20

In testimony whereof I affix my signature in presence of two witnesses.

JOHN SCHURY.
